UNITED STATES PATENT OFFICE

HYMAN ALBAN, OF CHICAGO, ILLINOIS.

POCKET.

1,133,906

Specification of Letters Patent. Patented Mar. 30, 1915.

Application filed January 18, 1913. Serial No. 742,871.

To all whom it may concern:

Be it known that I, HYMAN ALBAN, a citizen of the United States, residing at Chicago, in the county of Cook and State of Illinois, have invented new and useful Improvements in Pockets, of which the following is a specification.

The primary purpose of this invention is the provision of a pocket for the wearing apparel of men and youths to be placed in position when the original pocket becomes worn so as not to safely hold articles placed therein.

The invention in its specific adaptation provides a side pocket for trousers to be slipped into the original pocket and provided with fastening means for securing it in place, thereby avoiding the necessity for stitching and overcoming the urgency for repairing or mending the worn pocket.

The invention consists of the novel features, details of construction and combination of parts, which hereinafter will be more particularly set forth, illustrated in the accompanying drawing, and pointed out in the appended claim.

Referring to the drawing, forming a part of the specification, Figure 1 is a detail view, showing the application of the invention. Fig. 2 is a detail view of a pocket embodying the invention to be slipped within a worn pocket to take the place thereof. Fig. 3 is a detail view, showing more clearly the fastening means for securing the auxiliary or supplemental pocket within the main pocket.

Corresponding and like parts are referred to in the following description, and indicated in all the views of the drawing, by the same reference characters.

Inasmuch as the invention is specially adapted for men's and youths' trousers it is shown for use in this connection in the accompanying drawing, the auxiliary or supplemental pocket being of the general outline of the usual side pocket.

The numeral 1 designates a part of a pair of trousers and 2 the ordinary side pocket. To avoid confusion the pocket 2 is designated as the main pocket and 3 the auxiliary or supplemental pocket, which is slipped into the main pocket and secured in place therein. The auxiliary or supplemental pocket 3 is of the general outline of the main pocket 2 and may be constructed in a similar manner either of one or more pieces. The pocket 3 is open at one side, as indicated at

4, such opening corresponding with the side opening of the main pocket 2 so as to register therewith. The pocket 3 is somewhat smaller than the main pocket 2 so as to avoid any fullness or wrinkling. The lower ends of the side pieces comprising the pocket 3 are hemstitched or secured in any manner to prevent loose edge portions, thereby avoiding the formation of a welt in the lower part of the main pocket when the auxiliary pocket is in position. It is to be understood that the auxiliary pockets 3 are provided in rights and lefts for the different sides of the trousers. The edge portion of the front side of the pocket 3 bordering upon the opening 4 extends slightly beyond the edge portion of the rear side so as to come close to the outer edge of the front portion of the main pocket, whereby the hand may be easily introduced into the pocket when required. Fastenings 5 are secured to the upper and lower portions of the forward edge portion of the pocket 3 bordering upon the opening 4 and are adapted to engage the forward edge portion of the main pocket 2 so as to retain the supplemental pocket in position when slipped into the main pocket. Each of the fastenings 5 is of the nature of a clip, one member being secured to the edge portion of the pocket 3 and the other member adapted to engage the forward edge portion of the main pocket 2. The fastenings 5 consist of metal and are secured to the pocket 3 between the folded portions thereof, the projecting portions of the fastenings extending through slits formed in the fold.

When the main pocket 2 of a garment becomes thread bare or worn through so as to render it unsafe to place articles therein an auxiliary or supplemental pocket 3 may be obtained and slipped into the main pocket and secured therein by means of the fastenings 5 in the manner herein stated, said auxiliary pocket performing the office of the main pocket and avoiding the necessity for repairing or replacing the main pocket which is not always convenient and which frequently entails a greater expense than the application of the auxiliary pocket.

From the foregoing description, taken in connection with the accompanying drawing, the advantages of the construction and of the method of operation will be readily apparent to those skilled in the art to which the invention appertains, and while I have described the principle of operation of the

invention, together with the device which I now consider to be the best embodiment thereof, I desire to have it understood that the device shown is merely illustrative, and that such changes may be made when desired as are within the scope of the claim appended hereto.

Having thus described the invention what is claimed as new, is:—

- 10 An auxiliary pocket adapted to be introduced into a main pocket and conforming approximately in outline thereto and having a side opening at its upper end and having the edge portion of the front side projecting 15 beyond the edge portion of the rear side, and

fastenings applicable to the front edge of the main pocket when the auxiliary pocket is in position therein, said fastenings being secured in a folded edge of the auxiliary pocket at the upper and lower portions of its side opening extending through slits formed in the fold of such folded edge and terminating beyond the front side of said auxiliary pocket.

In testimony whereof I affix my signature 25 in presence of two witnesses.

HYMAN ALBAN.
